UNITED STATES PATENT OFFICE.

WILLIAM W. BORDEN, OF SAN LUIS REY, CALIFORNIA.

MECHANISM FOR CONVERTING MOTION.

SPECIFICATION forming part of Letters Patent No. 268,611, dated December 5, 1882.

Application filed June 27, 1882. (No model.)

To all whom it may concern:

Be it known that I, WILLIAM W. BORDEN, of San Luis Rey, of the county of San Diego and State of California, have invented a new and Improved Mechanism for Converting Motion, of which the following is a full, clear, and exact description.

The object of my invention is to provide a simple and efficient substitute for cranks.

To that end my invention consists in mechanism which combines a ratchet-wheel with a double rack fitted for oscillation for engaging the wheel at opposite sides in succession, as hereinafter described and claimed.

Reference is to be had to the accompanying drawings, forming a part of this specification, in which similar letters of reference indicate corresponding parts in all the figures.

Figure 1 is a side elevation of my improved mechanism. Fig. 2 is a longitudinal section of the same on line xx , Fig. 1. Fig. 3 is a cross-section on line yy of Fig. 1. Fig. 4 is a longitudinal section of the mechanism constructed in double form for obtaining a movement in either direction. Fig. 5 is a plan view of the mechanism as arranged for obtaining a reciprocating movement from a rotary movement; Fig. 6, a side view of the shifting weight.

The shaft to which a rotary motion is to be given is shown at a , and on this shaft is a wheel, b , that is formed with ratchet-teeth on one side of its rim.

c are the racks, connected together at their ends and formed on their side next the wheel b with ratchet-teeth for engaging the ratchet-teeth of the wheel; but the teeth of the racks are placed in reverse, so that one rack engages by a movement in one direction and the other by movement in the opposite direction.

To the rack-frame are connected longitudinal rods d , passing above and below a hub, e , on shaft a , so as to support the racks upon the said hub. The outer portion of the hub e is made as a rectangular frame, f , that is hung by horizontal pivots e' , to allow the rack-frame to oscillate transversely on the hub e and on an axis which is in the plane of the axis of the shaft. To one end of the rack-frame is connected a rod, g , by which power is applied for reciprocating the rack-frame, and the connection of this rod will be such as to allow the

oscillating movement of the rack. A spiral spring, h , is placed on the shaft a between the hub e and the wheel b for the purpose of relieving the shock of the oscillations of the rack-frame. 55

In operation, the reciprocating movement being given to the racks by the movement in one direction, the lower rack engages the ratchet-wheel and gives rotation thereto, the other rack slipping freely over the teeth of the wheel, and by the pressure thereon causing the rack-frame to oscillate so that the teeth that are in position for engaging the wheel are moved into engagement therewith fully, as illustrated in 65 Fig. 3. On the return movement the rack is oscillated in the other direction, and the other rack engages, thereby continuing the rotation in the same direction as before.

The device shown in Fig. 4 is the same mechanism in double form, and arranged so that the direction of revolution given to the ratchet-wheel may be reversed. There are two ratchet-wheels, b , and the racks c are made with ratchet-teeth upon both faces, and the racks 75 work between the two wheels b . The lever i is connected to the shaft a and fitted for moving the shaft endwise, thereby carrying either of the ratchet-wheels into engagement with the racks, according to the direction of revolution it is desired to obtain. 80

The device shown in Fig. 5 consists of a ratchet-wheel, as before described, and racks c , the rack-frame being hung on a rock-shaft d' in the frame of the machine. l are cams 85 placed for contact with the ends of the rack-frame at its extremes of movement, so as to give the required oscillating movement to the racks for shifting them in relation to the ratchet-wheel. With this form of mechanism, power 90 being applied to revolve the ratchet-wheels, the rack is given the reciprocating movement. To insure the connection of the opposite rack with the wheel in case the teeth do not coincide when the cam acts, I provide the shifting weight r . 95 (Shown in Fig. 5 and detail Fig. 6.) This weight is pivoted for lateral movement, and, being shifted from one side to the other by the cams, serves to hold the rack against the wheel, so that the teeth shall connect at the first movement of the wheel. Suitable stops are provided to limit the swing of the weight. 100

I am aware that rectangular motion has been converted into circular motion, and the reverse, by means of two racks of teeth on a frame having an axis parallel to the axis of a wheel operated upon by said racks alternately and by other similar devices, and I do not claim such, broadly; but

What I claim, and wish to secure by Letters Patent, is—

- 10 1. The combination, with the ratchet-wheel *b*, having teeth upon one of its faces, of the two racks *c*, attached to one face of a frame, which oscillates on a pivot which would intersect the axis of the wheel *b*, if extended, as shown and described.
- 15 2. The combination of the ratchet-wheel *b*, racks *c c*, the pivoted frame *f*, and hub *e*, sub-

stantially as shown and described, for operation as set forth.

3. The combination, with the frame provided with two racks of teeth, *c*, oscillating on an axis lying between said racks parallel to their plane, of two ratchet-wheels, *b*, and their shaft *a*, adjustable endwise, as shown and described. 20

4. The combination, with two bars connected together, provided with reverse ratchet-teeth, and fitted to oscillate their plane upon an axis parallel thereto, with a single ratchet-wheel and a balance-weight, as shown and described. 25
